METHOD AND APPARATUS FOR FABRICATING FOAM CORE WALLS

Harold S. McKnight, Jr., and Richard G. Schemehorn, Fort Wayne, and Neil V. Constantine, New Haven, Ind., assignors to General Industries, Inc., Fort Wayne, Ind.

Filed Aug. 1, 1962, Ser. No. 213,975
14 Claims. (Cl. 156—79)

The present invention relates to foam core walls and the method and apparatus for fabricating the same, and more particularly to a unique product, method and apparatus which lend themselves to mass production use in factories which manufacture prefabricated houses.

In the prefabrication of houses, it is customary to fabricate in a factory, on a mass production basis, certain basic components which go into the house structure and which require very little additional fabrication by carpenters at the site where the building is to be erected. Examples of these components are wall sections, partition paneling, roof trusses, roof sections and the like. More specifically, these and other basic components are mass produced on an assembly line basis in a factory for a variety of reasons among which are the reduction of costs as well as control of quality. When a customer purchases a house and desires to have the same erected on a building lot of his selection, the basic components are transported from the factory to the building site and there erected in primarily an assembly process with a minimum of labor. In many instances, the exterior walls are prefabricated and need only be erected on a previously provided foundation and joined together at the corners by some suitable means. Roof trusses, previously prefabricated, are mounted on the erected walls, following which substantially completed roofing panels are secured to the rafters thereby completing the shell. This operation is primarily one of assembling only prefabricated parts in contrast with the more or less conventional method of custom fabricating all of the walls, roof trusses and roof panels on the building site.

In the merchandising of such prefabricated houses, it is desirable to have a variety of different house sizes and designs, such that it becomes necessary to prefabricate the various components to different sizes and designs. This somewhat complicates mass production on an assembly line basis of the various different components such that some of the cost-reducing advantages involved in prefabrication are lost. The reasons for this are well known to persons skilled in the art. In order to minimize this complication, a number of prefabricators have designed the basic components, such as wall panels, in modules of varying sizes such that if a customer orders a house of a particular design, particular modules making up this design may be selected from the warehouse or suitable storage area and shipped to the building site. Since these modules conventionally include wall sections which are eight (8) foot long and of variable width and these wall sections are joined together in order to provide the finished wall design, there necessarily results a plurality of joints between wall sections which, because of the dimensional instability of the paneling due to changes in temperature and humidity, results in the joints working, opening and closing in accordance therewith. This, of course, is a feature not too desirable to the homeowner inasmuch as the joints are usually regarded as unsightly. Various methods have been proposed for covering and hiding the joints, batten strips being an example.

Another disadvantage residing in the prefabrication of modules for making up houses of different designs and sizes resides in the fact that the factory must have different assembly lines set up which are devoted exclusively to

2

one given size and design of module in order to retain the desirable features of quality control and economy of manufacture which is gained in prefabrication. However, the provision of these plurality of assembly lines requires additional plant, equipment and labor such that costs of production are correspondingly increased.

Keeping in mind that it is desirable for a prefabricator to have available a number of different designs and sizes of houses, the present invention is unique in that it overcomes the disadvantages of the prior methods and apparatuses used in prefabricating components in the respect of providing wall sections and the like which are prefabricated to length at the factory without any joints of the character hereinabove mentioned and which may be fabricated on a single production or assembly line which is geared to supply wall sections of any desired size. In the accomplishment of this salutary purpose, the present invention comprehends the prefabrication of wall paneling in continuous lengths which may be cut to any desired size as may be needed for a particular house design.

It is therefore an object of this invention to provide a panel structure of unique design which can be made on a continuous basis to any desired length. As a corollary, it is an object to provide a method for fabricating this paneling. As an additional object, apparatus for fabricating this wall is provided.

It is another object of this invention to provide plastic foam core walls which may be made on a continuous basis and cut to any desired length, these walls being provided with cases or raceways along the edges thereof for receiving top and bottom plates as well as electrical wiring. As a corollary, it is an object to provide a method and apparatus for fabricating these particular walls.

It is yet another object of this invention to provide foam core walls composed of two spaced-apart laminations of continuous length having sandwiched therebetween a suitable, expandable plastic material, the laminations being in themselves composed of individual sheets of plywood or similar type of building material uniquely joined together to provide the continuity in the lengths of the laminations. As a corollary, it is an object to provide a method and apparatus whereby this paneling may be continuously made on an assembly line basis with the finished wall being produced in a continuous length which may be cut to any desired size.

It is still another object of this invention to provide the walls of any of the aforementioned objects with a decorative finish which is also continuous in length.

Other objects will become apparent as the description proceeds.

The above-mentioned and other features and objects of this invention and the manner of attaining them will become more apparent and the invention itself will be best understood by reference to the following description of an embodiment of the invention taken in conjunction with the accompanying drawings, wherein:

FIG. 1 is a top plan view, partly in diagram, of typical apparatus used in practicing this invention;

FIG. 2 is a side elevation thereof;

FIG. 3 is a cross-sectional illustration of a scarf joint used in joining the edges of plywood sheets together;

FIG. 4 is a sectional illustration taken substantially along section line 4—4 of FIG. 1;

FIG. 5 is a cross-sectional illustration of one of the side mold rails used in the molding press of FIGS. 1, 2 and 4; and

FIG. 6 is a fragmentary end view of a typical wall fabricated in accordance with the principles of this invention.

Referring to the drawings, and more particularly to FIGS. 1 and 2, the apparatus typical of what may be

used in the fabrication of a continuous length of foam core wall is illustrated. First it should be noted that this apparatus is arranged in a straight line with certain of the raw material being fed into one end and the finished product emerging from the other end. More particularly, this apparatus comprises two parallel, vertically spaced-apart and horizontal conveyors or surfaces which may be said to define two spaced-apart, parallel and horizontal planes which may be considered as paths for the skins or laminations of the finished wall in the travel thereof from the beginning of the fabricating process to the end thereof. As shown in FIG. 2, the conveying or guiding surfaces include a framework 10 mounted on wheels 12 and having two sets of parallel, spaced-apart and horizontally extending conveyor rails 14 and 16 which extend in the direction of material travel. As shown in FIG. 1, the conveying or guiding surfaces may be composed of three spaced-apart and parallel bars or in the alternative they may include flat, smooth table surfaces or rollers, whichever may be desired.

At the right-hand end of the conveyor frame 10 and which may be secured thereto as a part thereof is a scarfing machine, generally indicated by the reference numeral 18. This machine may be of conventional construction and further may be purchased on the open market; however, in certain respects the design thereof is important as will appear from the following explanation. Primarily, the machine includes three elongated press elements 20, 22 and 24 which are shown in dashed lines. These elements 20, 22 and 24 are spaced apart to receive therebetween sheets 26 and 28, respectively, of plywood or the like. For example, the elements 20 and 22 are provided with flat, parallel facing surfaces which are spaced apart just sufficiently to slidingly receive the sheets 26 while the elements 22 and 24 are similarly formed to receive the sheets 28. Also, the press elements 20 and 24 desirably are mounted to be moved toward and away from the respective plywood sheets 26 and 28 so that during one period of operation these elements may be engaged with the plywood sheets and at another moment of time they may be moved away therefrom and correspondingly disengaged therefrom.

Suitable heating devices are included in the press elements 20, 22 and 24 such that heat may be quickly and readily transferred to the respective plywood sheets 26 and 28. Electrical or radio frequency heating, as desired, may be used; however, this invention in its broadest aspects contemplates the use of any type of heating which will serve the desired end purpose as will be explained in more detail hereinafter.

The particular purpose of the conveyor 10 and scarfing machine 18 will now be described. While the sheets 26 and 28 have already been described as being in the form of plywood, still, as will become apparent from the following description, sheets composed of different building materials may be used in this invention so long as they have the necessary characteristics to serve as outer laminations of the finished foam core wall. For the purpose of teaching this invention, the sheets 26 and 28 will be considered as being conventional 4-foot by 8-foot panels of $\frac{1}{4}$ inch or $\frac{3}{8}$ inch thick plywood; however, this invention is not to be construed as being limited thereto.

In the starting of the fabricating process of this invention, a plurality of sheets of plywood identified by the reference numerals 26, 26a, 26b, 28, 28a and 28b are laid on the two surfaces 16 and 14, respectively, as shown in the drawings, such that the longitudinal edges thereof abut as shown. However, before the sheets are laid onto the surfaces 14 and 16, the abutting edges thereof are beveled as shown at 30 in FIG. 3 for the purpose of providing a scarf joint. An elongated bevel having a tangent value of one-eighth (1/8) has been found to be satisfactory. However, prior to abutting these beveled, complementary surfaces, a suitable glue or adhesive is first applied thereto. Then sequentially, the individual,

adhesive coated and abutted joints are fitted into the scarfing machine in the position shown in FIGS. 1 and 2 with the press elements 20, 22 and 24 being in compressive engagement with the plywood sheets on both sides thereof for the entire length of the two joints. These two joints are indicated by the reference numerals 32 and 34, respectively. While in this position, the machine 18 is operated to apply heat to these joints 32 and 34 for the purpose of curing the glue or adhesive while the press elements 20, 22 and 24 hold the plywood sheets as well as the joints in position during this cure. After curing, the sheets of plywood are advanced toward the right as viewed in the drawings until the next joints 36 and 38 are brought into position in the scarfing machine where the same joint-securing process is repeated. This is followed by the joining of the other plywood sheets together such that two single, elongated and integrated panels or sheets emanate from the right-hand side of the scarfing machine. These integrated panels, indicated generally by the reference numerals 40 and 42, respectively, are composed of the individual panels 26, 28, etc. which have the edges thereof joined together as just explained. These integrated panels 40 and 42, in the manufacturing process, are advanced toward the right in generally the same spaced-apart, parallel and horizontal arrangements as originally defined by the two conveyor surfaces 14 and 16; however, there may be some sag and deviation from this strictly parallel relationship as will appear from the following description.

After the integrated panels 40 and 42 are formed, they are fed into a suitable molding press which is generally indicated by the reference numeral 44. This press generally includes a lower, extended area press plate 46 which is supported on legs 48 in a position such that the flat upper surface 50 thereof lies in a horizontal plane and preferably lies in the same plane as the conveyor surface 14.

An upper press plate 52 which may be substantially identical to the lower press plate 46 is disposed immediately above the lower plate 46 with the lower flat surface 54 thereof preferably lying in the plane of the conveyor surface 16. Also, it is desirable to have the upper plate 52 mounted on a suitable lift mechanism whereby it may be reciprocally moved toward and away from the lower press plate 46 as may be desired.

As shown more clearly in FIGS. 1 and 4, the two press plates 46 and 52 extend beyond the lateral or longitudinal edges of the two integrated panels 40 and 42 such that two mold side rails 56 and 58 may be inserted between the plate surfaces 50 and 54 as shown for the purpose of defining the mold cavity 60 between the portions of the two integrated panels 40 and 42 which are inserted between the two press plates 46 and 52. The side rails 56 and 58 are spaced apart and parallel and are adapted to engage the opposite lateral edges of the integrated panels 40 and 42 as shown. Generally speaking, these two rails 56 and 58 may be considered as elongated, straight bars having a plurality of spaced-apart apertures 62 therein which receive, respectively, a like plurality of steam probes or nozzles 64 and 66 which are connected to suitable manifolds 68 and 70, respectively, as shown. More particularly, the side rails 56 and 58 are substantially T-shaped in cross-section with the crossbar portion 72 being engaged respectively by the press plates 46 and 52 and the leg portion 74 (FIG. 5) having a width just sufficient to engage the facing surfaces of the two integrated panels 40 and 42 as shown. As a matter of fact, when the two rails 56 and 58 are properly positioned in the mold press 44, the lateral edges of the panels 40 and 42 are engaged with the undersides of the crossbars 72 thereof. The leg portions 74, which may be considered as mold inserts, thereupon extend inwardly a short distance (3 to 4 inches) toward each other between the two panels 40 and 42 for a purpose which will become apparent from the following description. The

distance which the bar portion 72 of the side rails extends beyond the respective leg portions 74 is selected to be equal to about the thickness of the plywood sheet which is being used. Therefore, if it is desired to use plywood sheets of different thicknesses in successive runs, it is only necessary to replace the crossbar portion 72 to accommodate the different thickness. Any type of joint may be used for mounting the crossbar portion 72 onto the leg portions 74, a typical tongue and groove connection being shown in FIG. 5.

For moving the side rails 56 and 58 a required distance toward and away from each other, two suitable fluid or air power cylinders 76 and 78 are used, the power cylinder 76 having a piston rod 80 connected to the side rail 56 as shown, and the cylinder 78 having a piston rod 82 connected to the side rail 58. By operation of these two cylinders 76 and 78, the two side rails 56 and 58 may be moved toward and away from each other, or in other words toward and away from the lateral edges of the integrated panels 40 and 42 as may be desired.

The steam probes 64 and 66, respectively, preferably consist of straight lengths of stainless steel or the like tubing having a multiplicity of tiny, longitudinally spaced apertures drilled therein through which steam may escape. The manifolds or headers 68 and 70 are preferably mounted so as to be movable toward and away from each other, or in other words may be moved outwardly to withdraw the steam probes 64 and 66 through the respective apertures in the side rails 56 and 58 until the steam probes 64 and 66 completely clear the mold cavity 60. By the same token, the headers 68 and 70 should be movable so as to move the respective probes 64 and 66 into the illustrated positions in the mold cavity 60.

A third bar 84 is used to close the left-hand end of the mold cavity 60 as shown in FIGS. 1 and 2. This particular bar 84 is preferably rectangular in cross-section and engages the left-hand ends of the two side rails 56 and 58 as shown. Also, this rail 84 has a width equal to the separation between the facing surfaces of the two integrated panels 40 and 42 so as to be engageable therewith.

The mold cavity 60 is now completely enclosed with the exception of the right-hand end as viewed in FIGS. 1 and 2. This closure is provided by a wall 86 of expanded plastic which completely fills the space between the two panels 40 and 42; however, this wall 86 is not provided until after the first section of the finished foam core wall of this invention is made. Therefore, in starting the process of this invention, it is necessary to provide another rail 84 in place of the wall 86 such that the mold cavity 60 will be completely enclosed on all four sides thereof.

A bead-injecting apparatus, indicated generally by the reference numeral 88 in FIG. 1, is provided with a nozzle 90 which enters the mold cavity 60 through a suitable aperture in the side rail 56. This aperture is indicated by the numeral 92 in FIG. 2. This apparatus 88 is diagrammatically illustrated; however, it is conventionally available on the open market and may take the form of any one of many different apparatuses available. As a matter of fact, instead of using this apparatus 88, the function performed thereby may be replaced by a manual operation which will be explained more fully hereinafter.

The operation of as much of the apparatus as thus far described will now be explained. Following the joining of the individual plywood sheet edges for forming the integrated panels 40 and 42 as already described, the right-hand end portions of these panels 40 and 42 are initially inserted fully between the press plates 46 and 52 to the positions illustrated in the figures. While in this position, the cylinders 76 and 78 are operated to force the mold rails 56 and 58 into engagement with the longitudinal edges of the panels 40 and 42 and the steam

probes 64 and 66 are inserted into the mold cavity 60 to the positions illustrated if this has not already been done. The end rail 84 is inserted in position and another end rail 84 is inserted between the panels 40 and 42 on the right-hand side of the mold cavity 60 for completely peripherally enclosing the same. The press plate 52 being reciprocable as previously explained is engaged with the crossbar portion 72. This results in closing the press plates 46 and 52 onto the panels.

With the mold cavity 60 thus closed, a suitable expandable plastic material is injected into the mold cavity 60. While this plastic material may take many different forms, expandable polystyrene is preferred inasmuch as this is initially obtained in the form of small beads, which after being preliminarily processed may be blown by the use of air into the mold cavity. Initially, this particular polystyrene material which is commercially available is in the form of small, dense crystal beads. However, before these beads are injected into the mold cavity 60, they are put through an unconfined expansion to the bulk density required in the finished article. This pre-expansion is provided by the simultaneous application of heat and agitation to a quantity of the beads for a desired period of time during which the beads are expanded in size to the density desired. These particular pre-expanded beads are the ones which are thereafter injected into the mold cavity 60 by means of the bead-injecting apparatus 88. A quantity of these pre-expanded, polystyrene beads are introduced into the mold cavity 60 filling the same, following which steam is admitted to the headers 68 and 70 which passes through the various steam probes 64 and 66 into the mold cavity 60. This results in heating the polystyrene beads causing them to expand and to bind together and also to fill the voids therebetween. After this full expansion has taken place, the steam to the headers 68 and 70 is cut off, following which the probes 64 and 66 are withdrawn from the cavity. The latent heat in the plastic serves to expand the same into the voids left by the steam probes 64 and 66. A certain time for cooling of the plastic material is required such that for this period of time the panels 40 and 42 are not moved but are permitted to remain stationary in the press plates 46 and 52. The press plates being in contact with the panels 40 and 42 resist distention thereof under the force of the expanding plastic. After the plastic material has sufficiently cooled so as to stop the further expansion thereof, the end rail 84 is removed from between the press plates, the two side rails 56 and 58 are separated slightly, perhaps an inch or so, by means of the power cylinders 76 and 78, and the press plate 52 being reciprocable may be lifted as desired. The integrated panels 40 and 42 are thereupon advanced toward the right to bring new panel portions into position between the press plates 46 and 52. Also, the left-hand edge of the plastic which was previously formed is now positioned flush with the right-hand ends of the mold rails 56 and 58 so as to provide an end wall for the mold cavity 60. The two side rails 56 and 58 are then moved back into engagement with the edges of the two panel portions 40 and 42, and the end rail 84 is reinstalled. The steam probes 64 and 66 are inserted into the mold cavity 60 and polystyrene beads are injected into the cavity as explained previously. The expansion process as just explained is repeated, and when the plastic material has sufficiently cooled, the integrated panels are advanced another step to the right until the left-hand edge of the foam plastic is brought into position to serve as a right-hand end wall of the mold cavity 60. Quite obviously, the right-hand end wall of the mold cavity which is positioned just inside the edges of the press plates 46 and 52 becomes integrated with the new section of plastic which is expanded in place.

In the finished product, it is desired that the expanded plastic be adhered securely to the facing surfaces of the two integrated panels 40 and 42. This is accomplished

by coating these particular surfaces either before the edges are joined together or after, with a suitable adhesive, a water-resistant type of urea-formaldehyde, resorcinol-formaldehyde, casein and rubber-resin solvent dispersions, being acceptable. Also, the adhesive may be thermoplastic such that it will soften and bond under the heat used to expand polystyrene. These adhesives may be applied to the facing surfaces of the panels immediately following emergence thereof from the scarfing machine 18 or may be applied to the panels prior to the time they are inserted into the scarfing machine 18. Insofar as this invention is concerned, an adhesive which will serve the purpose of bonding the expanded polystyrene plastic to the laminations 40 and 42 is all that is required.

The product which emerges from the press 44, as will now be apparent, is continuous in length, comprising laminations 40a and 42a which have sandwiched therebetween expanded polystyrene plastic 94. Since this paneling emerges from the press 44 in much the same manner as an extrusion, it may be cut to any length desired.

Since it is contemplated that the wall which emerges from the press 44 be used as walls and partitions in prefabricated houses or buildings, it will be required in many instances that at least one side of this panel have a decorative covering thereon. The application of this decorative covering in the form of wallpaper or the like may be easily and simply accomplished without the provision of any seams. As shown in FIG. 2, two rolls of wallpaper or the like, indicated by the numerals 96 and 98, respectively, are mounted on opposite sides of the finished wall. The webs 100 and 102 from these two rolls 96 and 98 are passed beneath two idler rollers 104 and 106, respectively, which are positioned adjacent to the outer surfaces of the laminations 40a and 42a such that the webs are laid directly onto these surfaces as the paneling is advanced toward the right. In order to adhere the paper to the panel surfaces, suitable liquid adhesives may be sprayed onto the panel surfaces by means of suitable spray heads 108 and 110, respectively. Thus, all in a single operation, a foam core wall with decorative covering on opposite sides thereof may be provided in a continuous length without any joints or seams being exposed. More particularly, the wall which emerges from a press 44 has a design which is more clearly shown in FIG. 6. Along the opposite longitudinal edges of the finished paneling are provided two raceways or voids indicated by the numeral 112. These raceways or voids 112 are provided, as will be apparent, by the particular shape of the side rails 56 and 58. The size of these raceways is made such as to receive, in one given situation, top and bottom plates as indicated by the dashed line configuration 114 in FIG. 6 and suitable electrical wiring 116. Such plates 114 may take the form of ordinary framing lumber such that in the illustration of FIG. 6, the wall will have a width of substantially two (2) inches. The raceway 112 is actually formed by molding the polystyrene to the particular shape shown, in the present instance the raceway being bounded on the opposite sides by the marginal edge portions of the two plywood panels 40a and 42a and on the bottom by the polystyrene itself. While the description thus far shows that two such raceways 112 are provided in the opposite longitudinal edges of the finished wall, as will be apparent to persons skilled in the art, only one such raceway or none at all may be provided. By merely changing the shape of the side rails 56 and 58, the desired result with respect to formation of the raceways may be obtained.

Similarly, while FIG. 2 illustrates the application of a decorative coating to both sides of the paneling, the same arrangement may be used for applying a coating or covering to one side only.

Finally, once the production of the foam core wall has been started and has progressed for some period

of time, immediately following the advancement of a length portion of the integrated panels 40 and 42 into the press 44, several new plywood sheets may be glued together while the expansion process is taking place in the mold 44. This is accomplished by rolling the frame 10 as well as the scarfing machine 18 toward the right until the endmost edges of the two integrated panels 40 and 42 are reached. Two new panels 26 and 28 are then abutted against these edges and glued into place by means of the scarfing machine 18. Since this process requires only a very short time and much less time than the expansion process occurring in the mold 44, three, four or more panels may be joined in this period of time by merely adding new sheets to the left-hand end of the integrated panels 40 and 42 and joining the edges thereof by means of the machine 18. Thus the machine 18 is moved toward the left in the joining process in steps, moving from joint to joint of the plywood sheets. Thus, the panels or laminations which are fed to the press 44 are continuous in length.

While we have described above the principles of our invention in connection with specific apparatus, it is to be clearly understood that this description is made only by way of example and not as a limitation to the scope of our invention.

What is claimed is:

1. The method of fabricating foam core walls in a continuous length comprising the steps of feeding a plurality of sheet-like panels along two parallel spaced-apart planar paths, said panels being edge-to-edge and defining the planes of the aforesaid paths, securing adjacent edges of said panels together in the respective planes thereof to provide two elongated integrated panels which are spaced apart and parallel, advancing said integrated panels along the respective paths thereof in successive steps for predetermined distances, sequentially forming successive, contiguous, individual, closed cavities at a common location between successive, discrete, contiguous length portions of said two integrated panels during the period of time between said successive steps, and introducing and expanding plastic material in said cavities at the aforesaid location following the formation thereof, thereby producing an elongated uninterrupted length of expanded foam plastic between the elongated integrated panels.

2. The method of claim 1 but including the step of providing an adhesive on the facing surfaces of said integrated panels which adheres said expanded plastic thereto.

3. The method of fabricating foam core walls in a continuous length comprising the steps of feeding a plurality of sheet-like panels along two parallel spaced-apart planar paths, said panels being edge-to-edge and defining the planes of the aforesaid paths, securing adjacent edges of said panels together in the respective planes thereof to provide two elongated integrated panels which are spaced apart and parallel, advancing said integrated panels along the respective paths thereof in successive steps for predetermined distances, providing an adhesive on the facing surfaces of said integrated panels, sequentially forming successive, contiguous, individual, closed cavities at a common location between successive discrete, contiguous length portions of said two integrated panels during the period of time between said successive steps, introducing and expanding plastic material in said cavities at the aforesaid location following the formation thereof, thereby providing an elongated uninterrupted length of expanded foam plastic between the elongated integrated panels, said expanded plastic material being adhered to said panels by said adhesive, and forming raceways in said expanded plastic material between and along the opposite longitudinal edge portions of said two panels during the time the plastic material is expanded, the raceways in the aforesaid length portions being collinear prolongations of each other.

4. The method of claim 1 and including the steps of

adhering said expanded plastic material to said panels, and securing said sheet-like panels together during the time said plastic material is being expanded.

5. The method of fabricating foam core walls in a continuous length comprising the steps of feeding a plurality of sheet-like panels along two parallel spaced-apart planar paths, said panels being edge-to-edge and defining the planes of the aforesaid paths, securing adjacent edges of said panels together in the respective planes thereof to provide two elongated integrated panels which are spaced apart and parallel, advancing said integrated panels along the respective paths thereof in successive steps for predetermined distances, forming a mold cavity which is closed on all sides between discrete length portions of said two integrated panels, said mold cavity being formed once during each of said advancing steps and contiguous with a preceding cavity, introducing plastic material into said mold cavity, and expanding said plastic material into engagement with said length portions of said two integrated panels and also into engagement with previously expanded plastic material to thereby provide an elongated uninterrupted length of expanded foam plastic between the elongated integrated panels.

6. The method of fabricating foam core walls in a continuous length comprising the steps of feeding a plurality of sheet-like panels along two parallel spaced-apart planar paths, said panels being edge-to-edge and defining the planes of the aforesaid paths, securing adjacent edges of said panels together in the respective planes thereof to provide two elongated integrated panels which are spaced apart and parallel, feeding parallel portions of said two integrated panels into a reciprocating molding press having two parallel and spaced-apart press plates which engage the opposite outer surfaces of said panel portions thereby positioning a mold cavity between said panel portions, providing opposite closing ends and sides between said panel portions around the marginal edges thereof for closing the periphery of said cavity, closing the press plates onto said panels for closing said cavity, introducing an expandable plastic into said cavity, expanding said plastic until it fills said cavity and engages the facing surfaces of said panel portions, opening said cavity advancing said panel portions with the expanded plastic therebetween through said molding press to a point at which two succeeding panel portions are moved into registry with said press and the edge of said expanded plastic is in position between said press plates to serve as one of said opposite cavity ends, closing the remaining end and sides of said cavity, and then repeating the introduction of expandable plastic into the latter mold cavity and expanding the same as before, thereby providing an additional section of expanded plastic paneling which is a continuation in length of the first section aforementioned.

7. Apparatus for producing foam core walls in a continuous length comprising means for conveying a plurality of sheet-like panels along two parallel spaced-apart planar paths with said panels being in edge-to-edge relation, means for securing contiguous edges of adjacent panels in said respective paths together to provide two elongated integrated panels which are spaced apart and parallel, a reciprocable molding press having upper and lower spaced-apart and parallel press plates which are engageable with the opposite outer surfaces of length portions of said two integrated panels, means closing the outer peripheral marginal edges of the space between said length portions of said two panels to thereby provide a mold cavity, means for introducing a plastic material into said cavity, and heat means selectively movable into and out of said cavity for expanding said plastic material while in said cavity.

8. Apparatus for producing foam core walls in a continuous length comprising a mechanism for joining edges of adjacent panels together, a molding press spaced from said mechanism for receiving two parallel spaced-apart

length portions of panels, means for conveying flat panels along two generally parallel spaced-apart paths between said mechanism and said press, said mechanism including means for joining in edge-to-edge relation a plurality of discrete panels in said two paths, respectively, for providing two integrated elongated panels which are in said paths, respectively, said press including two spaced-apart plates which are parallel and spaced apart, said two plates being relatively reciprocable into engagement with the opposite outer surfaces of length portions of said two integrated panels, respectively, said plates having a width at least as wide as said integrated panels, two spaced-apart elongated mold rails engageable with and parallel to the opposite longitudinal edge portions, respectively, of said length portions and extending between said two integrated panels to provide sides for a mold cavity between said length portions, an end rail engageable with and extending transversely between said length portions to provide a third side for said mold cavity which extends between said mold rails, a fourth side spaced from said end rail and extending between said mold rails for completing the closure of said mold cavity, said fourth side being closed by previously expanded and advanced foam plastic between said two integrated panels, means for inserting plastic material into said mold cavity, and heat means selectively movable into and out of said cavity for expanding said plastic material to fill completely said mold cavity to thereby form a section of the continuous length of wall.

9. Apparatus for producing foam core walls in a continuous length comprising a mechanism for joining edges of adjacent panels together, a molding press spaced from said mechanism for receiving two parallel spaced-apart length portions of panels, means for conveying flat panels along two generally parallel spaced-apart paths between said mechanism and said press, said mechanism including means for joining in edge-to-edge relation a plurality of discrete panels in said two paths, respectively, for providing two integrated elongated panels which are in said paths, respectively, said press including two spaced-apart plates which are parallel and spaced apart, said two plates being relatively reciprocable into engagement with the opposite outer surfaces of length portions of said two integrated panels, respectively, said plates having a width at least as wide as said integrated panels, two spaced-apart elongated mold rails engageable with and parallel to the opposite longitudinal edge portions, respectively, of said length portions and extending between said two integrated panels to provide sides for a mold cavity between said length portions, two elongated mold inserts adjacent and parallel to said mold rails respectively and interposed between the longitudinal marginal edges of said length portions to provide elongated raceways in the finished paneling, an end rail engageable with and extending transversely between said length portions to provide a third side for said mold cavity which extends between said mold rails, a fourth side spaced from said end rail and extending between said mold rails for completing the closure of said mold cavity, said fourth side being closed by previously expanded and advanced foam plastic between said two integrated panels, means for inserting plastic material into said mold cavity, and heat means selectively movable into and out of said cavity for expanding said plastic material to fill completely said mold cavity to thereby form a section of the continuous length of wall.

10. Apparatus for producing foam core walls in a continuous length comprising a mechanism for joining edges of adjacent panels together, a molding press spaced from said mechanism for receiving two parallel spaced-apart length portions of panels, means for conveying flat panels along two generally parallel spaced-apart paths between said mechanism and said press, said mechanism including means for joining in edge-to-edge relation a plu-

rality of discrete panels in said two paths, respectively, for providing two integrated elongated panels which are in said paths, respectively, said press including two spaced-apart plates which are parallel and spaced apart, said two plates being relatively reciprocable into engagement with the opposite outer surfaces of length portions of said two integrated panels, respectively, said plates having a width at least as wide as said integrated panels, two spaced-apart elongated mold rails engageable with and parallel to the opposite longitudinal edge portions, respectively, of said length portions and extending between said two integrated panels to provide sides for a mold cavity between said length portions, an end rail engageable with and extending transversely between said length portions to provide a third side for said mold cavity which extends between said mold rails, a fourth side spaced from said end rail and extending between said mold rails for completing the closure of said mold cavity, said fourth side being closed by previously expanded and advanced foam plastic between said two integrated panels, means for moving said mold rails away from said press and out of engagement with said length portions, means for inserting plastic material into said mold cavity, and heat means selectively movable into and out of said cavity for expanding said plastic material to fill completely said mold cavity to thereby form a section of the continuous length of wall.

11. Apparatus for producing foam core walls in a continuous length comprising a mechanism for joining edges of adjacent panels together, a molding press spaced from said mechanism for receiving two parallel spaced-apart length portions of panels, means for conveying flat panels along two generally parallel spaced-apart paths between said mechanism and said press, said mechanism including means for joining in edge-to-edge relation a plurality of discrete panels in said two paths, respectively, for providing two integrated elongated panels which are in said paths, respectively, said press including two spaced-apart plates which are parallel and spaced apart, said two plates being relatively reciprocable into engagement with the opposite outer surfaces of length portions of said two integrated panels, respectively, said plates having a width at least as wide as said integrated panels, two spaced-apart elongated mold rails engageable with and parallel to the opposite longitudinal edge portions, respectively, of said length portions and extending between said two integrated panels to provide sides for a mold cavity between said length portions, an end rail engageable with and extending transversely between said length portions to provide a third side for said mold cavity which extends between said mold rails, a fourth side spaced from said end rail and extending between said mold rails for completing the closure of said mold cavity, said fourth side being closed by previously expanded and advanced foam plastic between said two integrated panels, means for inserting plastic material into said mold cavity, and heat means selectively movable into and out of said cavity for expanding said plastic material to fill completely said mold cavity to thereby form a section of the continuous length of wall.

12. Apparatus for producing foam core walls in a continuous length comprising a mechanism for joining edges of adjacent panels together, molding press spaced from said mechanism for receiving two parallel spaced-apart length portions of panels, means for conveying flat panels along two generally parallel spaced-apart paths between said mechanism and said press, said mechanism including means for joining in edge-to-edge relation a plurality of discrete panels in said two paths, respectively, for providing two integrated elongated panels which are in said paths, respectively, said mechanism being movable toward and away from said press for joining a number of panel edges together to thereby lengthen said integrated panels, said press including two spaced-apart plates

5 which are parallel and spaced apart, said two plates being relatively reciprocable into engagement with the opposite outer surfaces of length portions of said two integrated panels, respectively, said plates having a width at least as wide as said integrated panels, two spaced-apart elongated mold rails engageable with and parallel to the opposite longitudinal edge portions, respectively, of said length portions and extending between said two integrated panels to provide for a mold cavity between said length portions, and end rail engageable with and extending transversely between said length portions to provide a third side for said mold cavity which extends between said mold rails, a fourth side spaced from said end rail and extending between said mold rails for completing the closure of said mold cavity, said fourth side being closed by previously expanded and advanced foam plastic between said two integrated panels, means for inserting plastic material into said mold cavity, and heat means selectively movable into and out of said cavity for expanding said plastic material to fill completely said mold cavity to thereby form a section of the continuous length of wall.

13. Apparatus for producing foam core walls in a continuous length comprising a mechanism for joining edges of adjacent panels together, a molding press spaced from said mechanism for receiving two parallel spaced-apart length portions of panels, means for conveying flat panels along two generally parallel spaced-apart paths between said mechanism and said press, said mechanism including means for joining in edge-to-edge relation a plurality of discrete panels in said two paths, respectively, for providing two integrated elongated panels which are in said paths, respectively, said press including two spaced-apart plates which are parallel and spaced apart, said two plates being relatively reciprocable into engagement with the opposite outer surfaces of length portions of said two integrated panels, respectively, said plates having a width at least as wide as said integrated panels, two spaced-apart elongated mold rails engageable with and parallel to the opposite longitudinal edge portions, respectively, of said length portions and extending between said two integrated panels to provide sides for a mold cavity between said length portions, said mold rails each having an elongated insert secured thereto and extending in parallelism therewith, said inserts extending toward each other but being spaced apart and operatively engaging the marginal longitudinal edges of said length portions, an end rail engageable with and extending transversely between said length portions to provide a third side for said mold cavity which extends between said mold rails, a fourth side spaced from said end rail and extending between said mold rails for completing the closure of said mold cavity, said fourth side being closed by previously expanded and advanced foam plastic between said two integrated panels, means for inserting plastic material into said mold cavity, and heat means selectively movable into and out of said cavity for expanding said plastic material to fill completely said mold cavity to thereby form a section of the continuous length of wall.

14. The apparatus of claim 8 wherein each mold rail comprises an elongated bar-like member having opposite parallel longitudinally extending surfaces, two elongated spacer elements removably secured to said two surfaces in parallelism therewith, said bar-like member having an elongated insert portion projecting beyond said elements which is narrower than the overall thickness of said member and said elements secured thereto, said member with said elements thereon being engageable by the upper and lower press plates, respectively, and said insert portion being insertable between and engageable with facing surface portions of said integrated panels whereby to provide raceways along the opposite longitudinal edges of the expanded plastic material in the finished wall.

UNITED STATES PATENT OFFICE
CERTIFICATE OF CORRECTION

Patent No. 3,159,514

December 1, 1964

Harold S. McKnight, Jr., et al.

It is hereby certified that error appears in the above numbered patent requiring correction and that the said Letters Patent should read as corrected below.

Column 2, line 30, for "cases" read -- chases --; column 12, line 9, after "provide" insert -- sides --; lines 16 and 17, for "betwee" read -- between --.

Signed and sealed this 20th day of April 1965.

(SEAL)
